US00D866781S

(12) **United States Design Patent** (10) Patent No.: **US D866,781 S**
(45) Date of Patent: ** Nov. 12, 2019

(54) **MASSAGE TOOL**
(71) Applicant: **Rocktape, Inc.**, Campbell, CA (US)
(72) Inventors: **Cullen Maxwell Maroney**, Campbell, CA (US); **Gregory van den Dries**, Los Gatos, CA (US); **Steven Capobianco**, Highlands Ranch, CO (US)
(73) Assignee: **Implus Footcare, LLC**, Durham, NC (US)
(**) Term: **15 Years**
(21) Appl. No.: **29/659,882**
(22) Filed: **Aug. 13, 2018**

CLAIM

The ornamental design for a massage tool, as shown and described.

DESCRIPTION

FIG. 1 is a perspective view of the massage tool in accordance with the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dot lines in FIG. 1-3 are included to represent the boundaries of the claimed design and form no part of the claimed design.

1 Claim, 2 Drawing Sheets

FIG. 1

FIG. 2

FIG. 3

FIG. 4

FIG. 5

FIG. 6

FIG. 7
